DRESSING MECHANISM FOR GRINDING WHEELS

Allan H. Candee and George O. Richmond,
Rochester, N. Y., assignors to Gleason Works,
Rochester, N. Y., a corporation of New York

Application June 15, 1937, Serial No. 148,341

7 Claims. (CL. 125—11)

The present invention relates to the dressing of grinding wheels.

It is general practice in grinding operations to employ grinding wheels of either cylindrical or conical form because such wheels can be trued or dressed in the simplest possible way, namely, by moving the contact point of a diamond or other suitable dressing tool in a straight line across the active surface of the wheel. In many operations, however, a straight profiled grinding wheel will not grind a surface of truly straight profile. Thus, a cylindrical or a conical wheel will not grind a truly straight profile on a helical surface such as, for instance, the side of a worm thread or the cam-relieved side surface of a hob tooth or of a face-mill cutter blade. To obtain a truly straight profile in such instances, the grinding wheel used should be dressed to a slightly curved profile. To dress a grinding wheel to a curved profile, however, a curved guide or template has heretofore been required and, where the curvature is slight, it is difficult to make such a guide or template accurately. The usual practice is to dress the wheel to a straight profile, (cylindrical or conical) and to accept the resulting slight curvature produced on the work. Often a slight departure from a straight profile or shape on the ground part is unimportant. In gear teeth, however, inaccuracies and variations of as small as 0.0001" are frequently objectionable and for that reason it has become more and more desirable to grind worm threads to a truly straight profile and to grind the relieved side surfaces of gear cutting tools such as hobs and face-mill cutter blades to truly straight profile.

The primary object of the present invention is to provide a simple, easily constructed and inexpensive apparatus for dressing a curved profile on a grinding wheel.

A further object of the invention is to provide apparatus which may readily be adapted to dress grinding wheels to curved profiles of various radii of curvature.

Still another object of the invention is to provide apparatus in which straight guides or templates may be employed to produce a curved profile on a grinding wheel. A straight guide or template is easy to make accurately and hence the difficulties previously encountered in the making of apparatus for dressing curved profiles on grinding wheels are obviated.

Other objects of the invention will be apparent hereinafter from the specification and from the recital of the appended claims.

In the drawings:

Fig. 1 is a side elevation showing a dressing mechanism built according to one of the simplest embodiments of the invention in use for dressing a curved profile upon a grinding wheel;

Fig. 2 is a fragmentary sectional view on the line 2—2 of Fig. 1;

Fig. 3 is a more or less diagrammatic view showing the dressing of a grinding wheel for grinding a worm or hob thread and illustrating the kinematics of the invention; and

Fig. 4 is a sectional view showing the grinding wheel spindle of a machine for relief-grinding face-mill gear cutters and a dressing mechanism constituting one embodiment of this invention for the dressing of the grinding wheel.

In dressing apparatus made according to the present invention, a curve is dressed on a grinding wheel by a combined reciprocating and pivotal movement of the dressing tool. The diamond or other dressing tool is secured to a reciprocable carrier that is so controlled by straight guides as to cause the contact point of the dressing tool to move in a path of known radius of curvature.

The invention may be embodied in various forms. In one embodiment, the reciprocable dresser carrier is provided with two angularly adjustable straight guide-members and the carrier is mounted so that these guide-members engage with and slide on a pair of spaced guide-rollers or pins as the carrier is reciprocated. The guide-members may be inclined to one another at different angles to vary the radius of curvature of the curve dressed upon the grinding wheel. In another embodiment of the invention, the dresser carrier is mounted to reciprocate in a support which is pivotally mounted for movement about a fixed pivot and the dresser carrier has a guide-member secured to it, which has a straight guide-surface that engages with and slides on a roller which is mounted upon a relatively fixed part of the dressing mechanism. The curvature dressed upon the grinding wheel depends, then, on the inclination of the guide-surface of the guide-member.

In any embodiment of the invention, the curve produced upon the grinding wheel is controlled by guide-members having straight guide-surfaces which can be or are set out of parallel. Straight guide surfaces are the simplest form to make accurately. Hence, the curve produced upon the grinding wheel may be made very accurately.

Reference will now be had to the drawings for a more detailed description of the invention.

In Figs. 1 and 2, a very simple embodiment of

the invention is illustrated. Here, 10 denotes a head or column in which there is journaled a spindle 11 that carries the grinding wheel 12 which is to be dressed. The spindle is driven by a pulley 13. The head 10 is shown as provided with an integral arm 14 to which is secured a block 15 by means of a screw 16. The block 15 carries two spaced pins 17 and 18.

The block 15 has a plane outside surface 20. 22 10 designates a block or carrier in which the diamond or other dressing tool 23 is secured. The carrier 22 has a plane under face that is adapted to seat and slide upon the plane surface 20 of the block 15.

15 Secured to the under face of the carrier 22 are a pair of guide-plates 25 and 26 which have straight guide-surfaces or edges 29 and 30, respectively. These plates are secured to the carrier 22 by screws 27 and 28, respectively. By 20 loosening these screws, the guide-plates 25 and 26 can be adjusted angularly on the carrier 22.

The carrier 22 is adapted to be moved manually over the guide block 15 to reciprocate the dressing tool 23 across the surface of the grinding wheel 12 while holding the guide-surfaces 29 and 30 firmly in contact with pins 27 and 28. If the guide-plates 25 and 26 are adjusted so that they are parallel to one another, the contact point of the dresser will then be moved in a straight line, 30 but if the guide-plates 25 and 26 are adjusted so that their guide surfaces are not parallel, the contact point of the dressing tool 23 will, then, follow a curved path such as that designated at 34 in Fig. 1. The position of the center of curvature 35 can be determined by simple kinematic principles. By varying the inclination of the guide-plates 25 and 26 to one another, the length of the radius of curvature dressed upon the grinding wheel may be varied.

40 The lines 31 and 32 in Fig. 1 denote normals through the centers of the guide-pins 17 and 18, respectively, and perpendicular to the straight edges of the guide-plates 25 and 26, respectively. The line 33 denotes a line which passes through 45 the contact point of the dressing tool and connects that point with the point of intersection of the lines 31 and 32. The center of curvature of the curve 30 dressed upon the grinding wheel is located approximately half-way between this 50 point of intersection and the point of the dressing tool, as may readily be determined.

A wheel such as shown in 12 in Fig. 1, dressed to a curved profile may be used in grinding the side surfaces of a worm thread or of the hob teeth 55 and when the wheel is dressed to a slight curvature, it may be used to correct the curvature on the ground surface, which occurs when a wheel with truly straight profile is used.

The kinematic principles underlying the present invention are illustrated in more detail in Fig. 3 which shows a grinding wheel 35 in position to grind one side 36 of the teeth or thread of a hob or worm 37 and which further shows a dressing mechanism made according to the present invention for dressing this wheel 35 to a curved profile.

The dressing mechanism as before, comprises a dressing tool 46 which is secured in a reciprocable carrier 41. This carrier 41 has a pair of guide-plates 42 and 43 secured to it by screws 44 and 45, respectively. The guide-plates 42 and 43 have straight side surfaces 48 and 49, respectively, which slide against the pins 46 and 47, respectively.

75 50 denotes a line drawn through the center of

the guide pin 46 parallel to the straight guide-edge 48 of the guide-plate 42. 51 denotes a line drawn through the center of the guide pin 47 parallel to the straight guide-edge 49 of the guide-plate 43. 52 is the point of intersection of these two lines 50 and 51. 54 denotes the circle upon which the point 52 moves as the dresser carrier 41 is reciprocated. 56 is a line drawn through the guide-pin 46 perpendicular to the straight edge 48 of the guide-plate 42. 57 is a line drawn 10 through the center of the guide-pin 47 perpendicular to the straight edge 49 of the guide-plate 43. These two lines intersect in a point 58. 59 is a line connecting the point 58 with the dressing tool 40. 60 is a line drawn through point 58 15 perpendicular to the line 59. 61 is a line drawn through the point of the dressing tool and the point 52 of intersection of the lines 50 and 51. 62 is the point of intersection of the lines 60 and 61. 63 is a line connecting the points 52 and 58. 64 is a point on the line 63 equi-distant from the points 52 and 58. 65 is a line connecting the point 64 20 with the point 62. By the principles of kinematics it is known that the point 66 of intersection of the line 65 with the line 59 is the center of curvature 25 of the path 67 of the dressing tool 40 as it moves across the grinding wheel.

The center of curvature 66 is seen to be approximately half-way between the diamond point 46 and the intersection point 58 of lines 56 and 57. 30 In actual practice, the radius of curvature from point 46 to point 66 is usually quite long, say more than one hundred inches.

By means of the above diagrammatic analysis, it is possible to determine the profile curvature 35 which will be dressed upon a grinding wheel by a dressing mechanism constructed according to this invention and to determine the required positions of the guide-plates 42 and 43.

We have described above, a form of mechanism 40 for dressing a grinding wheel of generally conical form for grinding a worm thread or hob teeth. In various other forms of gears or gear cutting tools, it is also necessary to grind a helical surface. Thus in relief-grinding face-mill gear cutter 45 blades, the relieved side surfaces may be ground by using a relative helical motion between the grinding wheel and the cutter as each blade of the cutter rotates under the grinding wheel. When cylindrical or conical forms of grinding wheels 50 are used, a slight curvature is produced on the blade profiles. To correct this, a slight compensating curvature is required on the wheel profile. Fig. 4 shows a dressing mechanism constructed according to the present invention for 55 dressing a generally cylindrical form of grinding wheel with a curved profile so that this grinding wheel may in turn be used to relief-grind side surfaces upon face-mill gear cutter blades which are of straight profile.

70 denotes the wheel head or support of a standard machine for relief-grinding face-mill gear cutters. 71 is the wheel spindle and 72 is the grinding wheel used in the relief-grinding operation which is to be dressed by the mechanism 65 of the present invention. 73 is a pulley for driving the wheel spindle for both dressing and grinding.

Pivotedly mounted upon the head 70 is a sleeve 70 or support 75. This sleeve or support 75 is connected to the head by means of a pivot-pin 76 which is secured in a block 77 that is fastened by screws 78 to the head 70. The sleeve or support 75 forms a guide for a bar 80 which reciprocates in the bore of the sleeve 75. The bar 80 carries a 75

post 81 to which is fastened an arm 82 which carries the dressing tool 84.

The post 81 is adjustable in the bar 80 to adjust the dressing tool in operative relation with the grinding wheel. For this purpose, the post 81 is made of reduced diameter at its upper end and threaded. It threads into a nut 85 which is secured against axial movement in the bar 80 by means of a thimble 86. The thimble is held in the bar by screws 87. The position of the post 81 and the dressing tool 84 can be adjusted very accurately by means of a micrometer dial 88 which is secured by the set-screw 89 to the nut 85.

15 The bar 80 is slotted adjacent its rear end to receive a cam or guide-plate 90 which is secured to the bar by screws 91. This guide-plate has a straight guide surface 92 which is inclined to the axis of the bar and of the sleeve 75. The 20 guide-plate 90 is adapted to slide on a roller 93 which is rotatably mounted in the head 70 and which extends through a slot 94 in the sleeve 75 so as to engage with the straight edge 92 of the 25 guide-plate.

25 The bar 80 may be reciprocated by any suitable means to pass the dressing tool 84 over the grinding wheel 72. As shown, the bar 80 is connected to the rod 95 of a piston which is adapted to reciprocate in a cylinder 96 that is secured to the sleeve or support 75. The diamond holder 30 may be reciprocated by fluid-pressure.

It is obvious that the grinding wheel may be dressed to a straight cylindrical form by providing a cam 90 with its guide surface 92 exactly 35 parallel to the axis of the sleeve 75 and by having the height adjustment of cam and roller such that axis of sleeve 75 is parallel to the axis of wheel spindle 71. By using a straight 40 guide-surface 92, however, which is somewhat inclined out of parallel to the axis of sleeve 75, various degrees of curvature may be obtained on the profile of the grinding wheel. The position of the center of curvature may be known by the 45 same general method of geometrical construction as explained in detail in connection with Fig. 3.

The line 100 is a line passing through the center of the roller 93 and normal to the straight edge 92 of the guide 90. The line 101 is a line passing through the center of the pivot pin 76 50 and normal to the bar 80. The line 102 is a line drawn from the point of the dressing tool 84 to the point of intersection of the lines 101 and 100. The center of curvature of the path 98 of the 55 dressing tool is at a point approximately equidistant between this point of intersection of the lines 100 and 101 and the point of the dressing tool.

While various embodiments of the invention have been illustrated, it will be understood that 60 the invention is capable of various further modifications and the present application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention 65 or the limits of the appended claims.

Having thus described our invention, what we claim is:

1. A dressing attachment for a grinding machine comprising a support adapted to be mounted adjacent the wheel which is to be dressed, a 75

slide reciprocable on said support, a dressing tool carried by said slide, spaced control means on said support controlling the movement of said slide, one of said control means comprising a fixed pivot about which the slide pivots on reciprocation thereof, and the other of said means comprising a templet and a follower, one of which is secured to the support and the other of which is secured to the slide, said templet having a straight guide surface engaging the follower and which is inclined to the direction of reciprocation of the slide. 5

2. A dressing attachment for a grinding machine comprising a support adapted to be mounted adjacent the wheel to be dressed, a slide movable on said support, a pair of spaced circular pins mounted on said support, and a pair of spaced straight-sided guide members carried by said slide and adapted to slide on said pins as the slide is reciprocated, said guide members being mounted on the slide to be adjustable angularly relative to one another to incline their guide surfaces out of parallel to each other. 10

3. A dressing attachment for rotary grinding wheels comprising a support adapted to be mounted adjacent the wheel to be dressed, a holder pivotally mounted on said support for movement about an axis inclined to the axis of the wheel, a slide reciprocable rectilinearly on said holder, a dresser carried by said slide, a roller mounted on said support and a guide member carried by said slide, said guide member having a straight edged guide-surface inclined out of parallel to the direction of reciprocation of the slide and adapted to ride on said roller as the slide is reciprocated to cause 30 said dressing tool to dress a curved surface on the grinding wheel. 35

4. A dressing attachment for a grinding machine comprising a support adapted to be mounted adjacent the wheel which is to be dressed, a slide reciprocable on said support, a dressing tool carried by the slide, a templet and a follower, one of which is secured to the slide and the other of which is secured to said support, means interposed between the dressing tool and the follower 40 and providing a fixed pivot for said slide in its reciprocable movement, said templet having a straight guide surface engaging the follower which is inclined to the direction of movement of said slide. 45

5. A dressing attachment for a grinding machine comprising a support adapted to be mounted adjacent the wheel to be dressed, a slide reciprocable on said support, a pair of straight edged non-parallel guides carried by one of said 55 members and a pair of contact members carried by the other of said members and adapted to ride on said guides, a dressing tool carried by one of said members and means for reciprocating said slide while maintaining the guides and contact members in contact. 60

6. A dressing attachment for a grinding machine comprising a support adapted to be mounted adjacent the grinding wheel which is to be dressed, a slide reciprocable on said support, a straight-profiled template mounted on the slide with its active surface inclined to the direction of movement of said slide, a follower secured to the support and engaging said template, a dressing tool mounted on said slide, and means forming a fixed pivot for said slide during its reciprocatory movement to cause the slide to pivot, as it reciprocates, about an axis inclined to the axis of the grinding wheel. 65

7. A dressing attachment for a grinding ma- 75

chine comprising a support adapted to be mounted adjacent the grinding wheel which is to be dressed, a slide reciprocable on said support, a template mounted on the slide and having an active surface of straight profile in a plane containing the axis of the grinding wheel and which is inclined to the axis of the wheel in that plane, a follower secured to the support and engaging

said template, a dressing tool mounted on said slide, and means forming a fixed pivot for said slide during its reciprocating movement, said means being so located that the slide will pivot, as it reciprocates, about a fixed axis inclined to the axis of the grinding wheel.
